SMOKER'S ASH RECEPTACLE TOP

William C. Panzer, Chicago, Ill.

Application March 3, 1949, Serial No. 1,180

Term of patent 14 years

(Cl. D85—2)

To all whom it may concern:

Be it known that I, William C. Panzer, a citizen of the United States, residing in Chicago, Cook County, Illinois, have invented a new, original, and ornamental Design for a Smoker's Ash Receptacle Top, of which the following is a specification, reference being had to the accompanying drawings, forming a part hereof.

Figure 2 is a side view thereof, as it appears with the tipper closure in tilted position.

I claim:

The ornamental design for a smoker's ash receptacle top, substantially as shown.

WILLIAM C. PANZER.
